DESIGN FOR A DRESS

Sabina De Pasquale, New York, N. Y.

Application January 29, 1940, Serial No. 89,825

Term of patent 3½ years

To all whom it may concern:

Be it known that, I, Sabina De Pasquale, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the dress disclosed of the specific embroidered collar member in association with the tucking on the sleeves and front blouse portion as shown.

I claim:

The ornamental design for a dress, substantially as shown and described.

SABINA DE PASQUALE.
